UNITED STATES PATENT OFFICE.

JAMES E. SKINNER, OF KINGMAN, KANSAS.

TRANSPOSITION-BRACKET FOR INSULATORs.

No. 902,455.

Specification of Letters Patent. Patented Oct. 27, 1908.

Application filed June 17, 1908. Serial No. 438,942.

To all whom it may concern:

Be it known that I, JAMES E. SKINNER, a citizen of the United States, and a resident of Kingman, in the county of Kingman and 5 State of Kansas, have made certain new and useful Improvements in Transportation-Brackets for Insulators, of which the following is a specification.

My invention is an improvement in trans- 10 position brackets for insulators, and consists in certain novel constructions and combinations of parts hereinafter described and claimed.

The object of the invention is to provide a 15 means for transposing wires such as telephone wires, etc., at suitable intervals whereby to equalize induction effects on the several wires, and without the use of complicated apparatus to be supported by the wires 20 themselves, and without the addition of extra cross arms on the pole.

Referring to the drawings forming a part hereof—Figure 1 is a plan view of the bracket, Fig. 2 is a section on the line 2—2 25 of Fig. 1, and Fig. 3 is a perspective view showing the bracket disassembled.

The present embodiment of my invention 30 comprises a bracket consisting of two sections A, B, substantially alike, and adapted to be arranged in crossed relation as shown in Fig. 1.

Each of the sections comprises a hub C, having a central opening c for receiving the bolt D, which secures it to the cross arms E, 35 on the pole, and a pair of diametrical arms G provided at their outer or free ends with bearings or sockets H.

One edge of each hub is regular but the other edge is provided with a pair of oppositely arranged segmental notches I, each of said notches comprising a segment of 90°, there being a segmental projection or lug of 90° between each of the notches.

The sections are arranged with the hubs in 45 superimposed relation on the pin D, and the lugs or projections of one hub fit into the notches of the other hub, thus effectually preventing any angular movement of the hubs with respect to each other.

50 The bearings or notches H are adapted to

receive insulator pins K, upon which are arranged the usual glass insulators M.

In using the bracket, the sections are arranged in superimposed relation as described on the bolt D and a nut N, threaded 55 on to the bolt secures them in place. The pins K and the insulators M are placed in position and the bracket is ready for the wires O, P.

The section B being below the section A, 60 the wire P is connected by a tie wire Q with one insulator of the section and extends thence longitudinally of the section to the other insulator, while the wire O is similarly 65 arranged with respect to the section A.

It will be evident from the description 70 that the wires are effectually transposed without danger of contact, and are retained in correct parallel relation between the transposition brackets.

I claim:

1. A transposition bracket for insulators, comprising two similar sections, each consisting of a hub, arms projecting in opposite directions from the hub, and bearings at the 75 ends of the arms for receiving the insulator pins, the edge of one hub being provided with segmental notches and the other with similarly shaped projections fitting within the notches whereby to retain the sections at 80 a predetermined angle with respect to each other, a bolt traversing the hubs for retaining the sections in position and for fixing them to a support.

2. A transposition bracket for insulators, 85 comprising two similar sections, each consisting of a hub, arms projecting in opposite directions from the hub, and bearings at the ends of the arms for receiving the insulator pins, the edge of one hub having notches and 90 the edge of the other projections engaging the notches for preventing angular movement of the hubs with respect to each other.

3. A transposition bracket for insulators, 95 comprising sections each consisting of a hub, provided with projecting arms and with means at the ends of the arms for receiving insulator pins, the edge of one hub being notched and the edge of the other having 100 projections for engaging the notches whereby

to prevent angular movement of the hubs with respect to each other.

4. A transposition bracket for insulators, comprising a pair of superimposed hubs, provided with radially projecting arms having bearings at the free ends thereof, and means in connection with the hubs for pre-

venting angular movement of one with respect to the other.

JAMES E. SKINNER.
